UNITED STATES PATENT OFFICE.

ALDRED JAMES JONES, OF DETROIT, MICHIGAN.

AUTOMOBILE CAUTION-SIGNAL.

1,391,120.

Specification of Letters Patent. Patented Sept. 20, 1921.

Application filed September 10, 1917. Serial No. 190,590.

To all whom it may concern:

Be it known that I, ALDRED J. JONES, a citizen of the United States, residing at Detroit, in the county of Wayne and State of Michigan, have invented a new and useful Automobile Caution-Signal, of which the following is a specification.

This invention has reference to automobile caution signals and its object is to provide a signal, especially of the semaphore type, arranged for operation by electric energy.

The invention comprises a casing which may be of columniform shape, housing a solenoid and having bearing for a rock shaft carrying a semaphore exterior to the casing. The solenoid has a peculiar connection to the shaft so as to provide a differential or eccentric action resulting in conservation of the energy employed, while means are provided whereby the core of the solenoid is constrained to operate to an extent as a dead-beat actuator for the semaphore.

The casing is made separable in part for ready access for installation and repairs, and provision is made for arresting the movement of the semaphore at predetermined limits in either direction.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be changed and modified so long as such changes and modifications mark no material departure from the salient features of the invention as expressed in the appended claims.

In the drawings—

Figure 1 is an outline view of an automobile with the caution signal attached and shown in side elevation.

Fig. 2 is an elevation of the observed side of the caution signal, showing the semaphore in the elevated or danger position.

Fig. 3 is a section on the line 3—3 of Fig. 2, but showing a semaphore in the lowered position.

Fig. 4 is a section similar to that of Fig. 3, but taken at right angles thereto.

Fig. 5 is a section on the line 5—5 of Fig. 3.

Fig. 6 is a perspective view of a removable side plate forming part of the casing.

Fig. 7 is a detail section of the shaft and encircling chain.

Fig. 8 is a rear view of the semaphore.

Referring to the drawings, there is shown a columniform casing 1, which in the particular construction shown, is of square cross section, and of the same cross-sectional area throughout. Such particular formation is, however, not obligatory.

The casing is provided with a removable top member 2, and a removable bottom member 3, each of which may be made fast to the casing by screws 4 or otherwise.

One side 5 of the body of the casing is made removable, being secured to the remainder of the casing by screws 6, or otherwise, so that when the side 5 is removed and the top 2 and bottom 3 are also removed, the interior of the casing is freely accessible for the installation of working parts of the structure, or inspection or repairs thereof.

Within the casing 1 near what constitutes the bottom thereof in the installed position of the device, there is a solenoid 7, mounted on a stirrup 8 made fast to the sides of the casing.

The solenoid is provided with a core 9, into one end of which is tapped one end of a screw rod 10, so arranged that its effective length may be varied by screwing into or out from the solenoid core, and when in desired position, the screw rod 10 is locked by a nut 11 on the rod.

The other end of the rod 10 has pivoted thereto one end of a multi-link chain 12, the other end of which is made fast to a pin 13, screwed radially into a rock shaft 14, traversing the casing and journaled in opposite sides thereof.

Exterior to the casing, one end of the shaft 14 has an angle extension 15, constituting a crank to which is secured a blade 16 forming a semaphore. One end 17, of the blade 16, is enlarged and is pierced by openings 18, covered by windows 19, 20, respectively, which may be made of any suitable transparent material such as glass, and these glass panes are held in place by rings 21, or in any other suitable manner.

Following the usual custom, one of the glass panes is colored red, and the other is colored green, but it will be understood that such colors may be varied if so desired.

The plate 5 is formed with an offset 22 on one long side and fast to this offset is a buffer block 23 of some soft material such as rubber. Fast to the blade 16, is another 5 buffer block 24, which may also be of rubber, and these blocks are so related that when the semaphore is in the lowered position, the buffer 24, engages the offset 22 on one face thereof, and when the semaphore is in the 10 raised position, the buffer block 23 is engaged by a tongue 25 on the enlarged portion 17 of the semaphore, which tongue may be conveniently produced by bending out a small part of the semaphore structure, such 15 structure being usually made of sheet metal, although not necessarily so.

The two colored panes 19 and 20 serve as signals at night, while for daylight signaling, the blade of the semaphore, which projects to one side of the axis of locking of the 20 semaphore, contains a warning word, such, as for instance, the word Caution, although any other word or warning indicia may be used.

25 Within the casing and carried by the removable side 5, is a forked bracket 26, so positioned that the forked portion straddles the threaded rod or stem 10 and so prevents any material displacement of the rod under 30 the ordinary shocks and jars of travel.

Carried by the casing near the top thereof so as to be back of either of the panes 19 or 20, is a bull's eye 27, and within the casing so as to project light through the bull's eye 35 is an electric lamp 28, mounted in a socket 29, to one terminal of which there is a lead 30, while the other terminal of which is connected by a wire 31 to the casing, so that the casing grounds the circuit.

40 One side of the solenoid 7 may be similarly grounded, while the other side is connected to a conductor 32, which, with the conductor or lead 30, is carried out of the casing through an insulating bushing 33 in the bottom member 3.

45 The casing 1 is or may be supported by a bracket 34, connected to any suitable part of the automobile, and preferably at the rear of the latter, as for instance, to one of the rear 50 wheel fenders.

For convenience of operation, the conductors 30 and 32 are carried to a controlling switch 34^a, which may be mounted upon the steering post of the vehicle, or at any other 55 convenient point, so as to be accessible to the operator of the vehicle.

When the vehicle is progressing forwardly 60 in a straight path, and other vehicles are following, and it is desired to deviate from such path, as for instance, to turn a corner, the operator touches a suitable part of the switch 34^a, whereupon the semaphore, which is normally pendent, is caused to assume a horizontal position by the energization of the 65 solenoid 7. This position is held so long as

the proper part of the switch 34^a remains closed.

The stirrup 8, if made of iron or steel, serves as a pole piece and stop member holding the core 9 in the indrawn position, the 70 travel of the core being such that when the semaphore is horizontal, the core is in engagement with the stirrup 8, and is held thereto magnetically, thus preventing any play of the semaphore due to vibration of 75 the core 9. The semaphore cannot vibrate in a rising direction because of the engagement of the finger 25 with the block 23.

When the semaphore is deenergized the overbalancing action of the semaphore 80 causes it to lift the core 9 so that the semaphore arm moves to a pendent position at which point the block 24 engages the offset 22.

Sometimes, especially in heavy or large 85 devices the core 9 is not heavy enough to approximately counterbalance the semaphore but is greatly overbalanced by the latter. In such case, a box or receptacle 35 is mounted on the screw rod 10, and is provided with 90 a cover 36, which may be screwed upon it. The box 35 is then supplied with some weighty material until the close approach to equilibrium between the core 9 and the semaphore arm is obtained. Then the work put 95 upon the solenoid 7 is reduced to a minimum despite the weight of the parts to be actuated and the electric current used is correspondingly reduced.

At night, the electric lamp 28 is energized 100 and so remains, wherefore the caution signal either displays a green light, indicating safety, or a red light, indicating danger, the latter light being displayed when a change 105 of course or running condition is contemplated. This warns a following automobile driver to take proper precautions to avoid collision.

The lock nut 11 is important in preventing 110 accidental change in adjustment of the parts and consequent failure of the signal to properly work.

The buffers 23 and 24 may be replaced by 115 any other suitable devices answering the same purpose.

What is claimed is—

1. A signal for automobiles, comprising a suitable casing, a rock shaft mounted in the casing and projecting therefrom, a signal device carried by and fast to the rock shaft exterior to the casing and at all times in visible position, electromagnetic means within the casing for rocking the signal device, and a chain connected at one end to the magnetic member and at the other end connected to the shaft, the connecting means comprising a screw stem threaded radially into the shaft and pivotally connected to the chain. 120

2. A signal for automobiles provided with 130

- electromagnetic operating means including a rockable shaft, a signal device carried by the shaft in visible position, a screw stem threaded into the shaft, and a chain connected at one end to the stem and at the other to the electromagnetic means, whereby the effective length of the chain may be varied by the screw stem.
3. A caution signal comprising a casing, a solenoid mounted therein, a core for the solenoid, a shaft journaled in the casing and extending therebeyond, indicating means on the shaft exterior to the casing, flexible connections between the core and the shaft and windable upon the latter for rotating the shaft, and a forked member on the casing straddling the connections between the core and shaft.
4. A caution signal for automobiles comprising a casing having a removable side, a solenoid mounted in the casing, signal means carried by the casing, a core for the solenoid, connections between the core and signal means, and a forked bracket carried by the removable side of the case and straddling the connections between the core and the signal means.
5. A caution signal for automobiles comprising a casing, a rockable shaft journaled therein and projecting therefrom, electromagnetic means in the casing for actuating the shaft, and a semaphore provided at one point with a finger and at another with a buffer, a casing having a side plate with a projection thereon in the path of the buffer on the semaphore and said projection being provided with a buffer in the path of the finger on the semaphore.
- In testimony that I claim the foregoing as my own, I have hereto affixed my signature in the presence of two witnesses.
